UNITED STATES PATENT OFFICE.

REISSUE

WILLIAM F. SEEL, OF DENVER, COLORADO.

APPARATUS FOR OPENING AND CLOSING AUTOMOBILE-DOORS.

1,123,405.

Specification of Letters Patent.

Patented Jan. 5, 1915.

Application filed May 16, 1914. Serial No. 839,037.

To all whom it may concern:

Be it known that I, WILLIAM F. SEEL, a citizen of the United States, residing at Denver, in the county of Denver and State of Colorado, have invented certain new and useful Improvements in Apparatus for Opening and Closing Automobile-Doors, of which the following is a specification.

This invention relates to improvements in means for opening and closing vehicle doors and is particularly adapted to automobiles having a plurality of doors to be opened and closed.

The object of the invention is to provide means located within convenient reach of the chauffeur whereby he can unlock and open any desired one of a plurality of doors and then close and lock the door without disturbing the others.

I accomplish the above and other objects which will hereinafter appear, by the mechanism illustrated in the accompanying drawings, in which—

Figure 1 is a top plan view of the skeleton or framework of an automobile body having two doors in front of the chauffeur's seat, and two doors in the rear of said seat. Fig. 2 is a longitudinal vertical section on the line 2—2 of Figs. 1 and 3. Fig. 3 is a cross section on the line 3—3 of Figs. 1 and 2. Fig. 4 is a view in side elevation of the operating lever and a portion of the connected mechanism, showing said parts detached from the automobile body, and also showing the rock-shafts carried by the lever in longitudinal section. Fig. 5 is a plan view of the parts seen from the line 5—5 of Fig. 4. Fig. 6 is a front elevation of the operating lever shown in Fig. 4, and Fig. 7 is a cross section on the line 7—7 of Figs. 4 and 6.

Like characters of reference indicate like parts throughout the several views of the drawings.

While I have shown my invention in connection with the skeleton or framework of an automobile adapted to carry two seats, each for two passengers, and said seats being arranged one behind the other with access to the body of the vehicle by doors on each side in front of each seat, it is obvious that my invention is applicable to other and different forms of vehicle bodies, and it will therefore be understood that the construction here shown is by way of example and for purposes of illustration only.

8 are the sills of the body having the usual pillars to which the doors are hinged and latched or locked.

9 are the doors in front of the chauffeur's seat and 10 the doors at the rear of said seat. The front edges of the doors are connected by hinges 11 with the corresponding front pillar. The top hinge for each door has an extension to which a horizontal link 12, (see Fig. 5), is pivoted at a suitable distance from the pintle of hinge 11 to secure adequate leverage or crank action to swing the door by force applied through said link 12. This force is applied to the link 12 by a crank 13 on the upper end of a rock shaft 14. The rock-shaft 14 is mounted in journals 15 secured to the pillar to which the door is hinged. The lower end of rock-shaft 14 terminates with a crank 16 which is connected with the end of a horizontal shaft 17 extending longitudinally of the vehicle body close to a side sill of the latter. The rock-shafts 14 of both of the front and rear doors on the same side of the body are connected through cranks 16 at their lower ends with separate horizontal shafts 17 and 18. The major portions of shafts 17 and 18 are slidingly mounted within a hollow shaft 19 to which an endwise reciprocating movement is imparted by means hereinafter to be described.

The doors 9 and 10 have their rear edges latched or locked to corresponding rear pillars of the vehicle body by means of latch-bolts 20 which are pivoted to levers 21 having spring connections 22 on the opposite side of the latch-bolt 20 from the pivot of the lever to hold the lever normally in locking position of its latch-bolt 20. The upward extension of lever 21 has the usual knob 22' for hand movement of the lever for unlocking the door, but the movement of lever 21 to draw the bolt 20 and unlock the door is accomplished by a push-bar 23 which is pivoted to lever 21 between spring 22 and the pivot of the lever, and which push-bar 23 terminates opposite a finger-extension 24 on rock-shaft 14. When the shaft 14 is rocked in the direction to press the finger-extension 24 against the end of push-bar 23 the lever 21 is moved to compress spring 22 and withdraw the latch-bar 20. This initial unlatching operation is secured, before the action of the rock-shaft 14 begins to open the door, by providing a suitable longitudinal slot 25 in the link 12 to

receive the end of the crank 13. By reason of the slot 25 the rock-shaft 14 can rock far enough to cause the latch to be withdrawn before the further rocking of shaft 14 begins 5 to open the door.

A hand-lever 26 is here shown as pivoted at 27 to the front seat-frame, in a space partitioned off between the two occupants of the front seat. A rock-shaft 28 is mounted 10 transversely of the vehicle body, under the front seat. This shaft has a downwardly extended arm 29, which is connected by a connecting-bar 30 with the lower end of the hand-lever 26. Each end of the rock-shaft 15 28 terminates with a crank 31, and each crank 31 is connected by a pitman 32 with the corresponding hollow shaft 19 on that side of the vehicle-body where the crank 31 in question is located. It was not heretofore stated but will be now, that doors 9 and 10 on both sides of the vehicle-body will be provided with the same latching and opening and closing mechanism as heretofore described and consequently there will be a hollow 25 shaft 19 on each side of the vehicle-body, extending longitudinally of the latter and consequently there will be a hollow shaft 19 adjacent to each crank 31 on the two ends of the rock-shaft 28. By the 30 mechanism thus far described it will be understood that the swinging of the hand-lever 26 about its pivot 27 will impart a corresponding endwise movement to the hollow shafts 19 on each side of the vehicle body.

35 The horizontal shafts 17 and 18 will each be provided with notches 33 to be engaged by rocking arms carried by the hollow shaft 19 whereby the longitudinal movement of shaft 19 may be imparted to either of the 40 shafts 17 or 18. The rocking arm 34, which is adapted to engage the notch 33 in shaft 18, is the end of a rock-shaft 35 bent at right angles. The shaft 35 is mounted in bearings 36 supported on the hollow shaft 45 19. The shaft 35 has its other end bent to form an arm 37 through which the power to rock the shaft is transmitted. The shaft 19 also supports a bearing 38 for a much shorter rock-shaft the projecting end of 50 which is bent at right angles to form the arm 39 which serves the double purpose of entering the notch 33 in shaft 17 and also forms the arm through which the power to rock the short rock-shaft is transmitted to 55 the latter.

The two doors for both sides of the vehicle body are provided with the same equipment, and I will now describe the mechanism by which the arms 37 and 39 may be 60 separately and swingingly moved at the hand-lever 26 to singly open or close any one of the four doors 9, 9, 10, 10. Supported by lateral extensions from hand-lever 26 and extending longitudinally of said hand-lever 65 is a shaft 40, on the lower end of which is an

arm 41 which is connected with the arm 39 by a rod 42, and secured to the opposite upper end of shaft 40 is a lateral finger-bar 43 in suitable position to be pressed by one of the fingers of the operator's hand while grasping the handle of lever 26. Such pressure will move the finger-bar 43, rock the shaft 40, thereby swinging arm 41 and through the rod 42 correspondingly swinging the arm 39, causing said arm 39 to enter the notch 33 in shaft 17 when, by the movement of the hollow shaft 19 through the swinging of hand-lever 26, the arm 39 is brought into register with notch 33. A connection is thus established with the rock-shaft 14, whereby the rear door 10 will be unlatched and opened by lowering the hand-lever 26 and closed and locked by moving the hand-lever in the reverse direction. Mounted on the rock-shaft 40 is a hollow 70 rock-shaft 44 on the lower end of which is an arm 45 and on the upper end of which is a finger-bar 46'. The arm 45 is connected up by rod 42 with the arm 47 which completes the mechanism for bringing the front door operating devices into play. Mounted on the hollow shaft 44 is a second hollow shaft 46 which has a lower arm 47 connected by a rod 42 with the arm 39 on the opposite side of the vehicle body, and this shaft 46 has a finger-bar 48 at its upper end for the same purpose as has been described in connection with the previously mentioned finger-bars. Mounted on the shaft 46 is a hollow shaft 49 which has an arm 50 at its 75 lower end connected by rod 42 with the arm 37 on the other side of the machine, and at the upper end of the shaft 49 is a finger-bar 51 for the purpose of manipulating said shaft 49 in the manner as described for the 80 other finger-bars.

From what has thus been said it is obvious that means is here provided for enabling the unlatching, opening, closing and latching mechanism for any one of the four doors 85 to be separately operated at the will of the chauffeur by the control of the mechanism attached to the hand-lever 26. When the arms 34 and 39 are rocked toward their respective notched shafts 18 and 17, a resilient 90 contact such as is necessary to prevent injury to the mechanism is secured by providing stop-lugs 52 on the rods 42 and springs 53 between said lugs 52 and the respective arms 37 and 39. The outer ends of the arms 95 42 are screw-threaded to receive nuts 54 by means of which the tension of the springs is regulated. This secures a yielding contact of the arms 34 and 39 with their notched shafts causing said arms to enter notch 33 100 when brought into register with the latter by the travel of the hollow shaft 19. The respective arms 41, 45, 47 and 50 are held normally against stops 55 and 56 by springs 57 (see Figs. 6 and 7). The tube 19 carry- 105

ing parts 34 and 35 is reciprocated by the rock-shaft 28. The rods 17 and 18 are normally free to slide in the tube, the springs 57 operating to keep the arms 34 and 39 out 5 of the recesses 33. When the finger-bars are operated, the arms 34 and 39 are moved into the recesses 33 and connect rods 17 and 18 to the tube 19 so that the doors may be swung. By swinging the desired one of the 10 finger-bars to the limit of its movement and simultaneously moving the lever 26, all of the doors being previously closed and latched, will unlatch and open that one of the doors which is connected with the finger-bar just manipulated with the movement of the lever 26. One or more of the doors can be controlled as above described by swinging a corresponding one or more of the finger-bars, coincident with the corresponding 15 movement of the lever 26.

As the operation of the mechanism has been described in connection with the detailed construction of same a further description of its operation is unnecessary.

25 While I have described my invention with more or less minuteness as regards details of construction and arrangement and as being embodied in certain precise forms, I do not desire to be limited thereto unduly 30 or any more than is pointed out in the claims. On the contrary, I contemplate all proper changes in form, construction, and arrangement, the omission of immaterial elements, and the substitution of equivalents, as circumstances may suggest or necessity render 35 expedient.

I claim:

1. In a vehicle, a hinged door, a rock-shaft having a crank-end, means connecting 40 the crank with the door the connection with the door being remote from the axis of the door-hinge, a second rock-shaft, means for connecting and disconnecting the latter to said first rock-shaft to rock the first shaft 45 when connected, means comprising a hand-lever for rocking the second shaft and means to connect the hand-lever with said last means.

2. In a vehicle, a hinged door, a substantially vertical rock-shaft having a crank-end, means connecting said crank with the door the connection being remote from the axis of the door-hinge, a second substantially horizontal rock-shaft, means for connecting 55 and disconnecting the second rock-shaft to the first one to rock the first one when connected, means comprising a hinged lever for rocking the second shaft, and means comprising a finger-bar pivoted to the hand-lever to connect the lever with said last means.

3. In a vehicle, a hinged door, a tube, a shaft carried by the tube, said shaft having an arm, means comprising a rod to swing the 60 door, said rod being normally free to slide

in the tube and said rod having a recess, means comprising a rock-shaft to slide the tube on the rod, and means comprising a hand-lever for rocking the last named shaft and means on the hand-lever to coöperate 70 the arm on the shaft with the recess in the rod.

4. In a vehicle, a hinged door, a tube, a shaft carried by the tube and having an arm, means comprising a rod to swing the 75 door, said rod being normally free to slide in the tube, said rod having a recess, means comprising a rock-shaft to slide the tube on the rod, means comprising a hand-lever for rocking the last named shaft, and means 80 comprising a finger-bar on the hand-lever to move the arm on the shaft carried by the tube into the recess of the rod to connect the rod and tube.

5. In a vehicle, a hinged door, a rock-shaft having a cranked end, means connecting the crank and door, the connection with the door being remote from the axis of the pintle of the door-hinge, means for rocking the shaft, a lock to hold the door closed, 85 means operated by the initial movement of the rock-shaft for unlocking the door before the further movement of the rock-shaft actuates the means for moving the door on its hinges, a second rock-shaft, means for connecting and disconnecting the two rock-shafts to rock the first one when connected, and means comprising a hand-lever for rocking the second shaft.

6. In a vehicle, a hinged door, a rock-shaft having a cranked end, a link pivoted at one end to the door remote from the axis of the pintle of the door-hinge, said link having a longitudinal slot in its other end through which the bent end of the crank on the rock-shaft passes, a lock to hold the door closed, and means operated by the initial movement of rock-shaft during the travel of its end in said slot of the link for unlocking the door before the further movement of the rock-shaft moves the link to swing the door on its hinges, a second rock-shaft, means for connecting and disconnecting the two rock-shafts to rock the first one when connected, and means comprising a hand-lever for 100 rocking the second shaft.

7. In a vehicle, a hinged door, a rock-shaft having a cranked end, means connecting the crank and door, the connection with the door being remote from the axis of the 105 pintle of the door-hinge, means for rocking the shaft, a finger-extension on the rock-shaft, a spring-lock to hold the door closed, and means comprising a push-bar contacted by the finger on the rock-shaft at the initial movement of the rock-shaft for releasing the lock to unlock the door before the further movement of the rock-shaft actuates the means for swinging the door on its 110 hinges.

8. In a vehicle, a hinged door, a tube, a shaft carried by the tube, said shaft having an arm, means comprising a rod to swing the door, said rod being normally free to slide 115

4

8. In a vehicle, a plurality of hinged doors, means for separately swinging the doors on their hinges, comprising a hand-lever, a plurality of independent finger-bars, one for each door, carried by said hand-lever, and means actuated by the individual movement of a finger-bar for connecting the hand-lever with the door-opening means of a door corresponding with the finger-bar which has been moved.

9. In a vehicle, a plurality of hinged doors, means for separately swinging the doors on their hinges, locks to hold the doors closed, a hand-lever, a plurality of independent finger-bars, one for each door, carried by the hand-lever, means actuated by the individual movement of a finger-bar for connecting the hand-lever with the door-opening means of a door corresponding with the finger-bar which has been moved, and means operated by the initial movement of the hand-lever for unlocking the door to be moved before the further movement of the hand-lever actuates said door-moving means.

10. In a vehicle, a plurality of hinged doors, a rock-shaft for each door having a cranked end, means connecting each door with its rock-shaft, said connection with the door being remote from the axis of the pintle of the hinge of that door, means to rock said rock shaft comprising a hand-lever,

ver, finger-bars, one for each door operating independently of each other and carried by the hand-lever, and means actuated by the movement of a finger-bar for connecting the lever with the rock-shaft of a corresponding one of said doors.

11. In a vehicle, a plurality of doors hinged on the same side of the vehicle, means comprising a rock-shaft for each door to swing the doors on their hinges, said rock-shafts having cranks, a horizontal hollow shaft, shafts connected with the crank of each rock-shaft and slidingly mounted in said hollow shaft and having notches, a swinging arm for each notched shaft, said swinging arms being carried by said hollow shaft, a hand-lever, a finger-bar for each door carried by said lever, and means actuated by the movement of a finger-bar for moving a corresponding one of said swinging arms into the notch of its notched shaft to thereby connect the hand-lever with the door-moving mechanism corresponding with the finger-bar that was moved.

In witness whereof, I have hereunto set my hand and seal at Denver, Colorado, this May, A. D. one thousand nine hundred and fourteen.

WILLIAM F. SEEL. [L.S.]
